UNITED STATES PATENT OFFICE.

HARRY D. ANDREWS, OF CINCINNATI, OHIO.

DISPLAY DEVICE.

Application filed April 13, 1926. Serial No. 101,768.

This invention relates to a display device which may be in the nature of an emblem, button, sign or advertising device.

The object of the invention is to provide a display device of this character which has a reversible display element adapted to carry diversified subject-matter on its two faces and also adapted to have either one of its faces readily moved to display position and releasably though securely held in such position.

A further object is to provide a device of this character having these advantages and which is of simple and durable construction, reliable in operation, attractive and ornamental in appearance and easy and comparatively inexpensive to manufacture.

Other objects and advantages reside in certain novel features of the construction, arrangement and combination of parts which will be hereinafter more fully described and particularly pointed out in the appended claims, reference being had to the accompanying drawings forming a part of this specification, and in which:—

Figure 1 is a perspective view showing one embodiment of the invention,

Figure 2 is a plan view thereof,

Figure 3 is an edge elevation showing one position of the parts,

Figure 4 is a view similar to Figure 3 showing another position of the parts,

Figure 5 is a perspective view showing another form of the invention,

Figure 6 is an edge elevational view thereof showing a device applied to a garment and in one position, and

Figure 7 is a view partly in perspective and partly in edge elevation showing another position of the parts illustrated in Figure 6.

Referring to the drawings, and more particularly to Figures 1 to 4, inclusive, numeral 1 designates a mounting means in the form of a bar having a slot 2 along its underportion. The bar 1 may be provided with a pin, clasp, or any other suitable means for securing it upon a supporting structure. The bar 1 has soldered, brazed, welded, or otherwise suitably secured to the front face thereof an emblem or plate-like member 3 which if not ornamented and filled to serve as an emblem bears suitable advertising indicia on its exposed face. A main display element, designated at 4, is provided and is preferably in the form of a plate having its upper end

beveled, as at 5, and designed to be received in the slot 2 of the bar 1. A stem 6 has its lower end secured to the crown portion of the upper end of the plate 4 and this stem 6 is suitably fitted in an opening 7 provided therefor in the bar 1. A coil spring 8 encircles the pin 6 and has its lower end abutting the top of the bar 1 and its upper end abutting the washer 9 engaged with the head 10 of the stem 6. The coil spring 8 is tensioned to resiliently urge the plate 4 upwardly so that the beveled upper edge 5 of the plate 4 is seated in the slot 2 of the bar 1. The stem 6 is not only a sliding fit 70 in the opening 7 but is also freely rotatable therein and consequently when the plate 4 is pulled downwardly, as shown in Figure 4, it may be turned through 180° or reversed. The opposite faces of the plate 4 have different indicia or subject-matter and either of these faces may be exposed to view if desired.

In the form of the invention shown in Figures 5, 6 and 7 mounting means is provided and includes a bar 20 having its upper end outturned, as at 21, and terminating in spaced bearing sleeves or ears 22. The mounting bar 20 may be fastened to clothing or to any other suitable supporting structure S by means of a stud 23 extending through the bar 20 and clamped to the clothing by means of nuts 24. A reversible display element, designated at 25, is provided and consists of a circular plate having a socket 26 at its center and a socket 27 fastened to its upper portion. The socket 26 contacts with a ball member 28 provided on the outer end of the stud 23. The socket 27 has a ball 29 universally fitted therein. The socket 27 may include a removable retaining ring to permit assembly of the ball 29 therewith and yet provided for the retention of the ball 29 therein. A short rod 30 is fixed to the ball at one end and to a shaft 31 at its other end, the rod 30 being secured to the intermediate portion of the shaft 31. The end portions of the shaft 31 are rotatably fitted in the bearing sleeves or ears 22. Both faces of the display element 25 carry advertising or other subject-matter and either face may be brought into play by disengaging the display element from its holding member, adjusting the display element to disclose the desired face and then again engaging the display element with its holding means. In this form of the invention

the holding means is the ball 28 and socket 25; whereas, in the other form of the invention the holding means is the beveled edge 5 of the display element and the slot 2. In 5 both cases the display elements are connected to the mounting means in such manner as to provide for adjusting movement of the display element in at least two planes.

I claim:

10. 1. A device of the character described comprising a bar having a slot, a plate carried by the bar, a display element, a stem carried by the display element, said bar having an opening in which the stem is slidably 15 and rotatably fitted, the upper edge of the display element being engaged with the slot of the bar, spring means co-operable with

the stem for engaging the display element and the slot, said spring and said stem being concealed by said plate.

20

2. A device of the character described comprising a bar having a slot longitudinally thereof, a display element having a bevelled edge portion engageable with the slot, a stem upstanding from the display element and transversely through the bar for rotating and sliding movement, spring means engaging said stem for urging the bevelled edge portion of the display element into engagement with the slot and means upstanding from the bar and serving to conceal the stem and spring means.
